UNITED STATES PATENT OFFICE.

CEYLON C. CORKRAN, WILLIAM WALLACE PAYNE, LEO DEUTSCH AND SAMUEL F. LENTZ, OF CHICAGO, ILLINOIS, ASSIGNEES TO THE TEXAS COMPANY, OF NEW YORK, N. Y., A CORPORATION OF TEXAS.

TRACK OILER.

Application filed, June 9, 1921. Serial No. 476,146.

To all whom it may concern:

Be it known that we, CEYLON C. CORKRAN, WILLIAM WALLACE PAYNE, LEO DEUTSCH, and SAMUEL F. LENTZ, citizens of the United States of America, and residents of Chicago, county of Cook, and State of Illinois, have invented certain new and useful Improvements in Track Oilers, of which the following is a specification, reference being had to the accompanying drawings, forming a part thereof.

Our invention relates to the lubrication of railway curves and has special reference to dispensing apparatus for applying suitable quantities of heavy oil to the edge of a curved rail.

One object of our invention is to provide a simple and effective dispensing device of the aforesaid character that shall be readily controlled as to the quantity of lubricant applied.

Another object is to insure that the oil shall not be applied to the top of the rail but shall, on the other hand, be applied and distributed so as to thoroughly lubricate the edge of the curved rail.

Other objects and advantages of our invention will be set forth hereinafter, and we will now describe the same with reference to the drawings and point out the novel features thereof in the appended claims.

Fig. 1 is an elevation of a dispensing device, shown in use, arranged and constructed in accordance with our invention and constituting one embodiment thereof.

Fig. 2 is a partial side elevation of the dispensing device, not in use, and with the outlet cap closed.

Fig. 3 is a sectional elevation showing the outlet end with its control valve, drawn to a larger scale.

Figs. 4, 5, 6 and 7 are sectional views taken respectively on the lines 4—4, 5—5, 6—6, and 7—7 of Fig. 3.

Like parts are designated by the same reference characters in all the figures.

The device illustrated comprises a tank or can 10 which constitutes the body of the device and has a long neck or dispensing tube 11, which terminates in a nozzle 12, having a protective casing 13, with an adjustable lid or cover 14.

The dispensing nozzle 12 is formed into a curved contact shoe 15, having a guide

rib or flange 16. There is an outlet port 17 in the rib or flange 16 close to the center of the contact shoe 15 through which oil from the can is discharged.

The quantity of the oil discharged is governed by a piston valve 18, which slides in a hollow boss 19 and is adapted to either entirely close the port 17 or graduate its opening, as desired. The spring 20 holds the valve in its closed position except when it is opened by the action of a control lever 21.

The can or body is adapted to be carried or supported in the hands of the operator by a handle 22 near the outer end of the tank or can and a handle 23 on the side of the tank near the discharge end. The lever 21 is pivoted at 24 on the handle 22 and is operatively connected to a lever 25 pivoted at 26 on the nozzle 12, by means of a connecting rod 27. The spring 20 is connected at one end to the nozzle 12 and at the opposite end to lever 25, the arrangement being such that when the lever 21 is actuated, the lever 25 is swung on its pivot and pulls the piston valve 18 outwardly in opposition to the action of the spring 20. The valve is thus opened when it is desired to discharge oil from the outlet port 17.

The oil is fed by gravity and the device when in use is held in an inclined position, as shown in Figs. 1 and 3, with the contact shoe 15, resting on the top of a rail 28 with the flange 16 in close engagement with the side of the rail to which the lubricant is to be applied and with the tank or body of the device uppermost.

When not in use, however, it is adapted to stand on the end of the can or body, so that the oil will have no tendency to leak through the opening.

In order that the oil, which is usually of high viscosity, may flow readily from the tank, a vent pipe 29 is provided. It opens into the casing 13 in position to take in air at one end and terminates within the tank or body near the side which is uppermost when the device is in use. Thus air can continually flow through the pipe into the tank to replace the oil which is discharged from the outlet port, without danger of leakage through the vent pipe.

The tank may be filled through an inlet port or opening provided with a screw cap

30. The casing 13 is arranged to catch any excess oil or grease which flows back on the outside of the nozzle 12 when the device is set on its end after having been in use, and it is provided with the hinged cover 14 adapted to be held open by a fastener 31, or in closed position by catch 32.

5 A brush or wiper 33 may be attached to flange 16 by spring 34, which is removably 10 mounted on the flange by screw 35, for the purpose of insuring a proper distribution of the oil on the edge of the rail. The brush or wiper, however, is not essential and may be omitted if desired.

15 It will, of course, be understood that the casing and lid for the nozzle may be dispensed with but this feature is advantageous for the purpose of keeping the whole exterior 20 of the device clean, particularly where the operator is likely to board passenger cars or trains and travel from one curve of the railway to another.

25 A device of preferred form and construction has been illustrated and described for the purpose of showing a way in which this invention may be used, but the inventive thought upon which this application is based, is broader than this illustrative embodiment thereof, and we therefore intend 30 no limitations other than those imposed by the appended claims.

What we claim is:

35 1. A track oiler comprising a storage tank, a discharge nozzle adapted to ride on the rail to be lubricated, a control valve at the nozzle, a handle on the storage tank, a control lever associated with the handle for governing the opening of the valve, and a casing for the nozzle having a cover or lid.

40 2. A track oiler comprising a storage tank, a discharge nozzle adapted to ride on the rail to be lubricated, a control valve at the nozzle, a handle on the storage tank, a control lever associated with the handle for governing the opening of the valve, a casing 45 for the nozzle having a cover or lid, and a

vent pipe terminating within the casing at one end and within the storage tank at the opposite end.

3. A track oiler comprising a nozzle in the form of a shoe adapted to ride on the rail, a flange thereon for engaging the side of the rail and having an opening therein, a storage chamber for supplying oil to the nozzle, and a control valve at the nozzle and means for governing the opening of the valve.

4. A track oiler comprising a nozzle in the form of a shoe adapted to ride on the rail, a flange thereon for engaging the side of the rail and having an opening therein, a storage chamber for supplying oil to the nozzle, a control valve slidably mounted to control the opening in the flange, a carrying handle on the storage tank, and a control lever on the handle connected to the valve.

5. A track oiler comprising a nozzle in the form of a shoe adapted to ride on the rail, a flange thereon for engaging the side of the rail and having an opening therein, a storage chamber for supplying oil to the nozzle, a piston valve for controlling said opening, a spring for closing the piston valve, a carrier handle on the storage tank, and means associated with the handle for governing the valve.

6. A track oiler comprising a storage tank, a pipe or extension connected thereto, a nozzle on the outer end of the extension having the form of a shoe adapted to ride on the rail, a box or casting attached to the extension for enclosing the nozzle, and a hinged lid for the casing adapted to be fastened open when the oiler is in use.

In witness whereof we have hereunto set our hands this 28th day of May 1921.
